Patented Sept. 2, 1902.

A. HANSON.

ADJUSTABLE SHADE BRACKET.

(Application filed Jan. 20, 1902.)

(No Model.)

Fig. 1.

UNITED STATES PATENT OFFICE.

AUGUST HANSON, OF NEW HAVEN, CONNECTICUT.

ADJUSTABLE SHADE-BRACKET.

SPECIFICATION forming part of Letters Patent No. 708,226, dated September 2, 1902.

Application filed January 20, 1902. Serial No. 90,500. (No model.)

To all whom it may concern:

Be it known that I, AUGUST HANSON, a citizen of the United States, residing at New Haven, in the county of New Haven and State 5 of Connecticut, have invented a new and useful Adjustable Shade-Bracket, of which the following is a specification.

This invention relates generally to curtain-fixtures, and more particularly to improved 10 adjustable shade-roller brackets adapted for use in connection with a curtain-pole bracket.

The object of the invention is to provide 15 an adjustable bracket capable of quick and easy adjustment, whereby shade-rollers of different lengths can be accommodated, and another object is to provide an adjustable bracket which when once adjusted can be securely held and all danger of displacement avoided.

20 With these objects in view the invention consists of the novel features of construction and combination, all of which will be fully described hereinafter and pointed out in the claims.

25 In the drawings forming a part of this specification, Figure 1 is a perspective view illustrating the practical application of my invention. Fig. 2 is a detail perspective view illustrating the combination of the curtain-pole bracket and shade-roller bracket. Fig. 3 is 30 a face view of the face-plate of the shade-roller bracket. Fig. 4 is a view taken from the rear of the same. Fig. 5 is a view illustrating in detail the securing means of the 35 shade-roller bracket. Fig. 6 is a horizontal sectional view of the said bracket, and Fig. 7 is a section on the line 7-7 of Fig. 6.

In carrying out my invention I employ a 40 face-plate A, said plate having a recess A' provided on the rear thereof for nearly its entire length, said recessed portion being slotted horizontally or longitudinally, as shown at A². The ends of the face-plate are provided with apertures A³, through which screws 45 are passed for the purpose of securing the face-plate to the window-frame. The face-plate also has shoulders A⁴ adjacent to its ends, and against one of its shoulders the brace-arm B⁴ of the curtain-pole bracket B is 50 secured by means of the same screw which fastens the face-plate to the window-frame, the supporting-arm B' being connected also

to the window-frame and provided with the usual construction of curved rest B², having the set-screw B³ for the purpose of securing 55 the pole in the said rest. The bracket-plate C has a reduced end C', which fits into and slides in the slot A². This bracket-plate is also formed with a flange C², which is arranged at a right angle to the plate C and 60 has an opening C³ produced therein and through which passes the bolt D, said bolt passing through the slot A² into the threaded opening E', produced in the block E, which fits into the recess A' and is provided 65 with an extension-lug E², which is adapted to fit into an opening C⁴, produced in the reduced end C' of the bracket-plate C, the flange C² and block E, together with the screw D, serving to hold the bracket-plate C 70 securely in any desired position. The bracket-plate C is of course provided with an opening C⁵ for the purpose of receiving the spindle of the shade-roller. Whenever it is desired to adjust the bracket-plate, the screw 75 D is slightly loosened and the plate moved along in either direction the desired distance, the block E sliding in the recess, while the bolt or screw slides in the slot, and after the desired position has been obtained the 80 screw or bolt is again tightened, thereby securely fitting the face-plate bracket, plate, and block together, and inasmuch as the block is provided with an extension-lug which fits into the reduced end of the bracket-plate it 85 will be readily understood that the said bracket-plate will be securely held against any possible displacement.

By having the curtain-pole bracket secured upon the face-plate of the shade-roller 90 bracket and bearing against the shouldered end of said face-plate all danger of the said curtain-pole bracket turning is avoided.

It will thus be seen that I provide a simple and efficient construction of curtain-fixture, 95 in which the shade-roller brackets can be adjusted at will without disturbing the curtain-pole brackets.

Having thus fully described my invention, what I claim as new, and desire to secure by 100 Letters Patent, is—

1. The combination with the recessed and slotted face-plate, of the shade-bracket having an apertured reduced end, a block ar-

ranged in the recess of the face-plate and having an extension fitting into the aperture of the reduced end of the shade-bracket, and means for connecting the bracket-plate and block as set forth.

2. The combination with the recessed and slotted face-plate of the shade-bracket having an apertured reduced end and a perforated angular flange and block arranged in

the recess of the face-plate, and having an extension fitting into the apertured end of the shade-bracket, and a bolt passing through the perforated flange and entering the said block as and for the purpose described.

AUGUST HANSON.
